UNITED STATES PATENT OFFICE.

JOHNSTON CROZIER WILEY, OF SIDNEY, OHIO, ASSIGNOR OF ONE HALF TO
GEORGE C. HUTCHISON, OF SAME PLACE.

GATE.

SPECIFICATION forming part of Letters Patent No. 367,258, dated July 26, 1887.

Application filed May 17, 1887. Serial No. 232,514. (No model.)

To all whom it may concern:

Be it known that I, JOHNSTON CROZIER WILEY, a citizen of the United States, and a resident of Sidney, in the county of Shelby and 5 State of Ohio, have invented certain new and useful Improvements in Gates; and I do hereby declare that the following is a full, clear, and exact description of the invention, which will enable others skilled in the art to which it applies to make and use the same, reference being had to the accompanying drawings, which form a part of this specification, and in which—

Figure 1 is a perspective view of my improved gate. Fig. 2 is a front view of the gate and its posts. Fig. 3 is a perspective view, seen from below, of the upper end of the hinge-post, the hinge stile of the gate, and of the operating-lever. Fig. 4 is an edge view of the gate seen from the hinge edge, and Fig. 5 is a 20 longitudinal vertical sectional view of the gate.

Similar numerals of reference indicate corresponding parts in all the figures.

My invention has relation to that class of 25 gates in which the upper end of the stile, at the hinge edge of the gate, is pivoted in the inner end of a lever pivoted upon the top of the hinge-post, and having means for tilting it by drawing suitable handles at the side of 30 the roadway, at both sides of the gate and at a distance from the same; and it consists in the improved construction and combination of parts of such a gate, as hereinafter more fully described and claimed.

In the accompanying drawings, the numeral 35 1 indicates the hinge stile, and 2 the latch-stile, of the gate, and these stiles are formed upon their inner faces with transverse notches or mortises 3, into which the ends of the rails 4 fit, the said ends being provided with round tenons 5, which fit in corresponding perforations, 6, in the stiles. Angle-irons 7 are preferably secured between the under sides of the rails and the inner sides of the stiles, bracing 40 the said rails.

Suitable rods or palings, 8, are secured vertically in the rails, and the gate is braced by means of diagonal brace-rods 9, having their united ends secured in a suitable notch, 10, at 45 the lower outer corner of the gate in the lower end of the latch-stile, while their inner ends

are inserted through perforations 11 in the lower corners of a triangular plate, 12, upon the hinge-stile, and have nuts 13 upon their screw-threaded ends, bearing against the plate, 55 and this plate is provided with a perforation, 14, at its upper corner, having the screw-threaded end of a rod, 15, inserted through it and the stile, having a nut, 16, bearing against the plate, the said rod extending along the top 60 of the upper rail of the gate and having its outer end secured in the latch-stile of the gate.

The hinge-post 17 is provided at its lower end with a common hook or pintle, 18, upon which a common eye, 19, upon the lower end 65 of the hinge-stile is pivoted, and at the upper end of the hinge-post a bracket, 20, is secured by means of a bolt, 21, passing into the post through a transverse slot, 22, in the lower portion of the bracket.

The upper horizontally-projecting portion 70 of the bracket is formed with a longitudinal slot, 23, within which the lower nutted end of a bolt, 24, is adjustably secured, and the flat arm 25 of a lever, 26, is pivoted upon this bolt, having a vertical bolt, 28, at the top of the hinge-stile of the gate, pivoted in its end, while the other end is formed into a semicircular frame, 29, having its periphery grooved. A chain, 30, is secured at its middle to the 75 middle of the grooved periphery of the frame, and rods 31 are secured to the ends of the chain, and have chains 32 at their ends, which chains pass over pulleys 33, supported from brackets 34 upon posts 35, and have weights 80 36 suspended from their ends, forming handles, as well as serving to hold the chains taut.

The main latch-post 37 is secured upon the opposite side of the roadway to the hinge-post, and has a mortise, 38, having beveled sides 39, 85 and a spring-latch, 40, of the usual construction, engages the said mortise.

Side latch-posts, 41, are secured at the side of the roadway and are provided with mortises 42, having the outer sides, 43, beveled, 90 and the spring-latch of the gate may engage these mortises when it is swung to either side. It will now be seen that if one of the chains is pulled the semicircular frame of the lever will be drawn toward that side, throwing the 95 upper end of the hinge-stile of the gate to the opposite side, thus first drawing the latch out

of the mortise in the latch-post, and thereupon throwing the center of gravity toward that side of the gate, causing the gate to be tilted to that side. The latch will now engage the mortise in the side latch-post at the side to which the gate swings, which will be the side opposite to the side from which the chain was pulled; and when the vehicle or passenger has passed through the gate it may again be closed by pulling the chain at the post which the vehicle or passenger will now pass, this operation being similar to the operation in gates of this class.

The latch will at all times spring into the mortise of the latch-post when coming opposite to the same, being normally forced out by its spring.

It will be seen that by having the joints between the rails and the stiles, as described, formed with tenons and fitting the tenons in the perforations and the ends of the rails in the transverse notches in the stiles, the gate-panel will not be liable to sag, and the diagonal brace-rods having their nutted ends in the lower perforations in the triangular plate, and the upper horizontal brace-rod having its screw-threaded and nutted end fitting in the upper perforation, the said rods may be tightened up against each other by the nuts, drawing the upper portion of the gate together, while at the same time drawing the lower portion of the gate upward and inward, so that all sagging of the gate will be entirely prevented or may be entirely remedied.

35 By having the longitudinal slot in the horizontal portion of the bracket supporting the

upper pivot of the gate and the transverse slot in the lower portion of the bracket the bracket may be adjusted to take up any slight sagging of the hinge-post, the bracket being 40 adjusted to the opposite side of the sag of the post, if the post sags in a plane parallel to the roadway, while the pivotal bolt of the lever may be adjusted if the post should sag transverse to the roadway. 45

Having thus described my invention, I claim and desire to secure by Letters Patent of the United States—

In a gate, the combination of the hinge-post, a bracket having a transverse slot at its lower end secured upon a bolt in the side of the post and having a longitudinal slot in its horizontal portion, a lever fulcrumed upon a bolt secured adjustably in the longitudinal slot of the bracket and having a semicircular frame at 55 one end formed with a groove, and a perforation in its other end, a gate-panel hinged upon a pintle at the lower end of the hinge-post and having a pivot at the upper end of the hinge end pivoted in the perforated end of the 60 lever, and chains secured to the middle of the semicircular frame and passing over suitable supports at the side of the roadway, at both sides of the gate, as and for the purpose shown and set forth. 65

In testimony that I claim the foregoing as my own I have hereunto affixed my signature in presence of two witnesses.

JOHNSTON CROZIER WILEY.
